UNITED STATES PATENT OFFICE.

GEORG. W. STEFFENS, OF BROOKLYN, NEW YORK, ASSIGNOR TO THE CRAIGHEAD & KINTZ COMPANY, OF BALLARDVALE, MASSACHUSETTS.

INKSTAND.

SPECIFICATION forming part of Letters Patent No. 459,829, dated September 22, 1891.

Application filed April 23, 1891. Serial No. 390,091. (No model.)

To all whom it may concern:

Be it known that I, GEORG. W. STEFFENS, of Brooklyn, Kings county, and State of New York, have invented a certain new and useful Improvement in Inkstands, of which the 5 following is a specification.

I will describe an inkstand embodying my improvement, and then point out the novel features in a claim.

10 In the accompanying drawings, Figure 1 is a perspective view of an inkstand embodying my improvement with the cover closed. Fig. 2 is a similar view with the cover open. Fig. 3 is a horizontal section. Fig. 4 is a 15 vertical section.

Similar letters of reference designate corresponding parts in all the figures.

A designates the body of the inkstand. It may be made of metal and of any approved 20 design. When it is made of metal, it may contain an ink-well of glass or analogous material.

B designates the cover of the inkstand. It may advantageously be made of metal, although it can be made of any other suitable 25 material. It will be made of a design appropriate to the design of the body of the inkstand. For instance, the body of the inkstand may be made to represent the upper 30 portion of a man, and the cover the head of a man.

The body of the inkstand is provided with a vertical socket *a* and the cover with a vertical pin *b*, surmounted by a shoulder *b'*. The pin *b* fits in the socket *a*, and the shoulder *b'* 35 rests upon the top of the socket. Obviously the cover may be swung horizontally upon a vertical axis formed by the combination of the pin *b* with the socket *a*, so as to cover or uncover the body of the inkstand. The 40 shoulder *b'* will support the bottom of the cover slightly above the top of the inkstand, so that the two parts will not become stuck together by ink on the upper surface of the inkstand.

45 What I claim as my invention, and desire to secure by Letters Patent, is—

The combination, with the body of an inkstand having a vertical socket, of a cover therefor having a vertical pin fitting said socket 50 and a shoulder surrounding the pin between the body of the inkstand and the cover, substantially as specified.

In testimony whereof I have signed my name to this specification in the presence of 55 two subscribing witnesses.

GEORG. W. STEFFENS.
